UNITED STATES PATENT OFFICE.

HENRI NERCAM, OF CONSTANTINE, ALGERIE, FRANCE.

FRAME FOR STRETCHING CANVASES AND THE LIKE.

Application filed July 9, 1920. Serial No. 395,145.

To all whom it may concern:

Be it known that HENRI NERCAM, citizen of the Republic of France, residing at Constantine, Algerie, France, 36 Avenue Bien-
fait, has invented certain new and useful Improvements in Frames for Stretching Canvases and the like, of which the following is a specification.

This invention relates to improvements in extensible stretching frames for holding and stretching various sizes of sheets, painting-canvas, papers and similar materials, and its object is to provide a longitudinally and laterally, or two-way extensible frame in which no recesses occur at the four corners and edges supporting the canvas or sheets on the extended frame.

This frame comprises four corner bars connected together at the corners by mortice and tenon joints and formed with overlayed sliding arms with unilevel supporting edges and permanently assembled corner pieces.

In large frames, where it is required in consideration of their size, an extensible cross-bar, or bars, may be provided.

Each corner bar comprises two arms integral with mitre pieces having the full width and thickness of a complete bar and of any suitable length limited only by the strength which must be left for the provision of the mortices and tenons or keys for assembling the mitre corners. The corner portions form shoulders or stops for the sliding arms of the frame and their outer bearing surfaces conform to those of the arms, while the outer bearing edge of all the members of the frame always preserve an uninterrupted uniform alignment.

To render the invention clear I will describe the same fully with reference to the accompanying drawings, in which:

Figure 1 is a front elevation slightly shown in perspective, of the complete frame in a partly extended condition.

Figure 2 is a transverse section taken on the line 2—2 of Figure 1 shown to a larger scale.

Figure 3 is a perspective view showing the assemblage of the cross-bar to the frame portion.

The angle bars 1 and 2 are arranged so as to slide along one another and with closed frame they show a uniformly shaped face, that is to say, the closed frame has an uninterrupted border portion and recessed bead which has longitudinal slots 3.

The corner pieces stand up flush with the outer arm of each bar and are morticed to receive the tenons or tongues 4 and keys 5 so as to provide rigid corner points. The arms 1 have the border portions 6 undercut so as to form an acute angled edge 7, see Figure 2. The arms 2 are recessed so as to form a bed for the arms 1 and have a wedge-shaped ledge or check 8 with knife edge 9 raised to meet the edge 7, as is clearly shown in Figure 2. An essential feature of the invention is that the extended frame shall have aligned bearer edges for the canvas or other material.

The sliding arms can be firmly retained in an adjusted position by screw bolts formed with a flat square head 19 and inserted in corresponding slots 3 of the sliding arms. The latter may be marked so as to facilitate accurate adjustment.

Large frames are fitted with extensible cross bars composed of three parts 10, 11, 12 of which the part 10 is of length to fit between the closed bars of the frame, while the parts 11 and 12 extend for half such length. The parts 11 and 12 are removably connected to the bars of the frame and held rigid by wedges 16, their ends being slotted as at 15 to engage with a filling piece 18 while bolts 17 allow for displacement, see Figure 3. Corresponding slots 13 in the parts 10, 11 and 12 receive bolts 14 and together form means permitting of lateral extension of the frame.

The space which will separate each slot from the next is optional and decided particularly by the solidity which must be left to the sliding bars.

The length of the slots is likewise optional and will likewise be determined by the solidity necessary for the bars nevertheless it should be at least that of the space left between successive slots plus twice the diameter of the assembly bolts so that by the movements of extension or shortening there will always be found openings permitting the assembly bolts to pass through the thickness of the bars.

It follows that the width to give to the slots will be equivalent to the diameter of the bolts together with a slight play. The bolts to be used should preferably have flat heads; convenient length and thickness and be at least two in number.

To constitute a complete frame, four corner bars are assembled after having been

roughly arranged for the desired length as is done for ordinary wedge frames and there will be fixed to its outer edge by pins or brads the sheets or paper for stretching.

5 Having described my invention, what I claim is:—

1. In an extensible stretching frame for holding and stretching various sizes of painting canvases, angle bars to slide along one 10 another to form a closed extensible frame, said angle bars comprising lower arms recessed to form a wedge-edged bed for the upper bars, inclined face on the upper bars to fit the said recesses of the lower bars to 15 obtain aligned bearer edges all around the frame, in order to assure an absolutely plane surface of the stretched canvas and avoid folding of the same, and means to retain the bars in the adjusted position, substantially as described.
2. In an extensible stretching frame for 20

holding and stretching various sizes of painting canvases, angle bars to slide along one another to form a closed extensible frame, mitre corners for them, mortices and tenons 25 for assembling the mitre corners, said bars comprising lower arms recessed to form a wedge edged bed for the upper bars, undercut border portions on the upper bars to fit the recesses of the lower arms to obtain aligned 30 bearer edges all around the frame and to secure thereby an absolutely plane surface of the stretched canvas, and means to fix the arms in the adjusted position, substantially as described.

35 In testimony whereof he has affixed his signature in presence of two witnesses.

HENRI NERCAM.
